HAND FIRE EXTINGUISHER

Filed Feb. 21, 1924

Inventor:

Wolfgang Magg

By *Linne & Sonnenfeld*
Attorney.

UNITED STATES PATENT OFFICE.

WOLFGANG MAGG, OF VIENNA, AUSTRIA.

HAND FIRE EXTINGUISHER.

Application filed February 21, 1924, Serial No. 694,332, and in Austria March 23, 1923.

This invention relates to hand fire extinguishers.

Hand fire extinguishers have already been proposed in which the "rising pipe" in the cover of the container for the liquid is so arranged as to be longitudinally displaceable so that it may be caused to act upon the vessel containing the acid.

In these forms of construction the acid containing vessel is connected with the rising pipe, so that it, together with the rising pipe, may be inserted or removed through the upper aperture of the container. This arrangement presents the disadvantage that through the frequent removal of the rising pipe, if there is careless handling, a possibility always to be contemplated in the case of such an apparatus, the pipe may be dent- 10 ed and bent and also may become loose at the joint connecting the rising pipe with the acid container, or its perforated containing cylinder or cylindrical strainer.

These disadvantages are obviated in the hand fire extinguisher according to the present invention, by an extension rigidly connected with the sliding rising pipe, which extension acts as a striking appliance for effecting the fracture of the acid carrying vessel.

30 The appended drawing shows a vertical section of one form of construction of the invention.

In the drawing 1 indicates the peripheral wall of the liquid container or receptacle which is closed so as to be liquid tight and gas tight, by means of a seamed joint with the bottom 2 and the top 3. The bottom 2 has inserted in it an internally screw-threaded sleeve 4 through which the perforated cylinder, or cylindrical strainer 6, for the reception of the glass vessel 5 containing the acid, is inserted into the container, after the perforated cylinder 6 has been closed by the screwed closure 7, the thread of closure 45 7 engaging the screw-thread in the sleeve 4. The joint is made gas-tight by means of a lead ring and a packing filler.

The glass vessel 5 is provided with a recess or cavity at its lower end said recess 50 engaging a stud or projection 8 on the screwed closure 7 whereon the glass vessel 5 is suitably supported and its fracture is facilitated.

The top 3 of the container has inserted in 55 it a stuffing box 9 through which the rising pipe 10 passes to the outside, a tight joint

being secured by means of the gland 11 and sleeve nut 12. The upper portion 23 of the pipe 10 is mounted to slide freely through a stuffing box 9 and terminates at its upper end 60 in a knob 13 adjacent which there is located a short tubular extension or pipe 14.

15 indicates an extension upon pipe 10 situated above the upper end of the perforated cylinder 6. 65

The upper end 16 of cylinder 6 is provided with a perforation through which a pin 17 extends, which pin, together with a plate 18 rests on the glass vessel 5.

One or several packing discs 19 are provided to prevent any oscillation of the glass vessel in the perforated cylinder 6. 70

A blow delivered upon the knob 13, forces the pipe 10 downwardly whereby the extension 15 strikes the pin 17 and smashes the 75 glass vessel 5 containing the acid. The pipe 10 is provided with a branch pipe 24 connected to it above the extension 15 and this branch pipe is provided with a sieve or strainer 20 in order to prevent the entry of 80 splinters from the glass vessel.

A forked clip 21, on the inside of the container 1, holds the pipe 24 and therefore pipe 10 against turning movement in the stuffing box 9 so that the lower end of the pipe is 85 always placed diametrically opposite to the handle 22, hence at the lowest point of the apparatus during its manipulation.

The striking pin 17 may be dispensed with if the extension 15 of the rising pipe 10 is 90 so shaped that it can act directly upon the vessel containing the acid.

Claims:

1. A hand fire extinguisher comprising a liquid receptacle, a frangible acid vessel in 95 said liquid receptacle, a cylinder for said acid vessel, a plate upon the upper end of the acid vessel, a projection on said plate, a perforation in the cylinder for the passage of said projection, a centrally disposed discharge pipe, said pipe being longitudinally movable, and an extension on the pipe adapted when the pipe is forced inwards to contact with the projection on the plate upon the upper end of the acid vessel and cause 100 the vessel to be fractured.

2. A hand fire extinguisher comprising a liquid receptacle, closures at each end of 110 said receptacle, a frangible acid vessel in said liquid receptacle, a cylinder for said acid vessel, a plate upon the upper end of the acid vessel, a projection upon said plate,

a perforation in the cylinder for the passage of said projection, a centrally disposed discharge pipe, said pipe being longitudinally movable, an extension on the pipe adapted 5 when the pipe is forced inwards to contact with the projection on the plate upon the upper end of the acid vessel and cause the vessel to be fractured, a stud at the lower end of the cylinder for the acid vessel designed to support said vessel and assist in fracturing same.

3. A hand fire extinguisher comprising a liquid receptacle, a closure for said receptacle, a stuffing box and gland in said closure, a longitudinally movable escape pipe passing through said stuffing box and gland, a port upon said pipe for discharge of extinguishing liquid, a foot upon said pipe, a branch pipe upon said escape pipe leading 15 to the lower portion of the liquid receptacle,

a clip upon the wall of the receptacle engaging said branch pipe, a closure for the lower end of the liquid receptacle, an opening in said closure, a screwed closure for said opening, a perforated cylinder for an acid vessel upon said closure, a frangible acid vessel in said cylinder, a recess in the bottom of said receptacle, a stud upon the upper surface of the screwed closure upon which the acid vessel rests, a plate at the 25 upper end of the acid vessel, a projection upon said plate, a perforation in the upper end of the cylinder for the acid vessel for the passage of the projection, said projection being disposed beneath the foot upon the 30 escape pipe.

In testimony whereof I have hereunto set my hand the 8th day of February, 1924.

WOLFGANG MAGG.
